D. PARKS

HEEL GOUGING MACHINE

Filed Feb. 8, 1922

UNITED STATES PATENT OFFICE.

DENNIS PARKS, OF ST. LOUIS, MISSOURI.

HEEL-GOUGING MACHINE.

Application filed February 8, 1922. Serial No. 535,015.

To all whom it may concern:

Be it known that I, DENNIS PARKS, a citizen of the United States, residing in the city of St. Louis and State of Missouri, have invented new and useful Improvements in Heel-Gouging Machines, of which the following is a specification.

This invention relates to an improved machine for use in removing a portion of the material from the upper side of a heel-blank for the purpose of providing a concave recess forming a seat to receive the heel portion of the sole.

It has been the common practice heretofore, to provide this recess by attaching a rand around the upper part of the heel-blank, particularly in the case of whole lift heels. In heel-blanks formed of pieced lifts, attempts have been made to provide this recess by gouging out the central portion of the upper lift from near the back to the breast edge of the heel. In either case, that is to say, where the use of a rand, or gouging, has been employed, the heel-blank is placed in a mold and subjected to very great pressure in a suitable compress.

In the gouging operation as heretofore practiced, the cut was made from a point near the back of the heel-blank and extended in an inclined direction to the breast. The recess thus formed does not conform in shape either to the mold of the compress or to the rounded configuration of the heel portion of the sole to which it is to be applied. The desired shape is imparted in the compress, but owing to the unequal depth of the gouge and its lack of conformity in shape to the mold, the heel-blank would be subjected to greater pressure at some points than others and very often the leather of the heel-blank would be blackened or burned at such points.

It should be stated that where a leather board is used, the bottom lift, that is, the one next to the sole, may be readily provided with the concave recess; but in the case of all leather heels, either of whole or pieced lifts, either a rand must be used or the heel-blank must be gouged, as above explained.

It is the general object of the present invention to provide a gouging machine which

will enable a concave recess to be provided in the top of the heel-blank of uniform depth from the point of incision of the cutter to the breast of the heel, the recess thus formed conforming in shape and extension to the heel portion of the sole which is to be seated therein, and enabling the heel-blank to be compressed in the mold of the compress with the application of uniform pressure throughout, thus avoiding the undesirable burning of the heel-blank.

In addition to the above general object, the invention has for subsidiary objects, improved means for centering the heel-blank relative to its line of movement as it passes to the gouge, to provide that the recess to be formed in the top of the heel-blank by the gouge shall be symmetrically disposed with reference to the longitudinal center of the heel-blank; to provide novel means for adjusting the machine to accommodate heel-blanks of different heights, and to provide certain novel details of construction whereby the general and subsidiary objects of the invention are accomplished.

The invention is illustrated in the accompanying drawing in which—

Figure 1 is a plan view of the machine; Figure 2 is a longitudinal sectional view of the upper portion thereof taken on the line 2—2 of Figure 1 and illustrating the position of the heel-blank prior to the beginning of the gouging operation;

Figure 3 is a similar sectional view showing a portion of the mechanism illustrated in Figure 2 but showing the position of the parts as the heel-blank is being gouged.

Figure 4 is a plan view of a heel-blank which has been gouged to provide a recess in its upper side; and

Figure 5 is a perspective view of the device for centering or positioning the heel lift as it passes to the gouger.

Referring now to the drawing, the numeral 1 indicates a main frame which may be mounted in any suitable manner, as by being bolted to a table or other character of support or by being supplied with legs or standards, the particular manner of mounting the frame not being shown. Journaled in side bars 2 of this main frame is

a shaft 3 having secured on one end a clutch member 4. Rotatably mounted on the shaft is a pulley 5 which is provided with a clutch member 6. The numeral 7 indicates a pulley shift which embraces opposite sides of an annular flange 8 surrounding the hub of the pulley and is pivotally mounted at 9 on the bracket 10 secured on a frame member 2 and is further provided with a handle 11 for turning it in one direction or the other to move the clutch member 6 into or out of engagement with the clutch member 4. The pulley is driven by an ordinary belt (not shown) from a suitable source of power. Secured on the shaft 3 adjacent to the inner sides of the frame members 2 are two sprocket wheels 12 and loosely mounted on a shaft 13 at the opposite end of the frame are two sprocket wheels 14, the shaft 13 being slidably mounted at its end in slots 15 provided in the side frame members 2 and being screwthreaded at either end to receive the threaded portion of set screws 16, the smooth shank portion of which are rotatably mounted in flanges 17 provided at the ends of the frame members 2 and the ends of which set screws bear against the outside of said flanges. By turning these set screws in a clockwise direction, the shaft 13 may be moved outward to adjust the tension of sprocket chains 18 mounted on the two sets of sprocket wheels 12, 14. The sprocket chains 18 are connected at two or more points by parallel cross-bars 19 which act as push bars to move the heel-blanks into engagement with a gouger 20. This gouger is adjustably secured on the inclined under side of the solid portion 21 of a casting which extends substantially from end to end of the frame and is located between the side frame members 2. This casting is hollowed out on its under side beyond the gouger 20, as indicated at 22, and provides on its upper side a flat surface forming a table 23. About centrally of its length, this upper portion or table is provided with a transverse slot 24 through which the gouger 20 projects to a desired distance above the upper surface or table 23 of said casting. At opposite ends the casting is provided with downwardly curved extensions 25 which extend over and slightly below the respective shafts 3 and 13. The side frame members 2 are connected on their upper sides by two cross-bars 26, 27 respectively, and on the cross-bar 27 there is mounted a triangular shaped casting 28 in which is mounted a similarly shaped magazine 29, of tin or other suitable material, which is held in position by means of a screw 30 passing through a flange 31 projecting rearwardly from the casting and screwed into a block 32 fitted in the crotch of the magazine 29.

As heretofore set forth, a leading characteristic of the present invention is the provision of means for effecting a uniform depth of gouge or recess in the heel-blank. This is accomplished by the mechanism that will now be described.

At the bottom and rear side of the casting 28 is provided a relatively wide rectangular extension 33 which is transversely bored to receive a pivot pin 34. The numeral 35 indicates an arm which is provided on its outer end with a weight 36 adjustably mounted thereon by means of a set screw 37. This arm is enlarged and bifurcated at its inner end, as indicated at 38, to embrace the sides of the extension 33 and the said bifurcations are apertured to receive pivot pin 34. Pivotally mounted on the under side of the arm 35 near the inner end thereof, as indicated at 39, is a dog 40, the under side of which is provided with a projection 41 and beyond the projection, with a relatively flat portion 42 forming a tread or bearing surface for engaging the upper side of the heel-blank, as will be presently described. In its normal position the toe 43 of this dog occupies an elevated position, as shown in Figure 2, and after each operation, is returned to this position by means of a spring. To this end the pivot 39 is in the form of an elongated pin, as shown in Figure 1, which projects beyond one side of the dog and of the arm 35, and is encircled by a coil spring 44, one end of which is secured to the pivot pin 39 and the other end of which bears against the rear side of the dog, as shown more particularly in Figure 2, thus operating normally to hold the dog in the elevated position shown in this figure. To provide that the heel-blank passing to the gouger 20 shall be properly positioned or centered with reference thereto, I devised the device shown in Figure 5, which comprises a yoke 45 having laterally projecting parallel arms 46 which are pivotally mounted on the pin 34, washers 47 being interposed between said arms and the sides 38 of the bifurcated head of arm 35. The legs 48 of this centering device are inclined inwardly from the inner edges thereof, that is to say, from the edges which will be first engaged by the rounded end of the heel-blank as it passes to the gouger, such inclined portions being indicated at 48^a, so that if the heel-blank is out of position, it will readily slide over one or the other of said inclined sides so that the longitudinal center of the heel will lie midway between the two legs 48 and consequently will coincide with the transverse center of the gouger 20. Secured in a longitudinal recess 49 provided in the upper part of the table 23, is a leaf spring 50, the free end of which projects over the recess 24 and is slightly upturned, as indicated at 51. The purpose of this spring is to hold the rounded or forward

end portion of the lift elevated until the latter is depressed by the dog 40, as will now be described.

In operation a column of heel-blanks is placed in the magazine 29, the bottom heel-blank of the column resting upon the spring 50. The shaft 3 having been placed in rotation by moving the pulley shift 7, the sprocket chain 18 is set in motion by the driven sprocket wheels 12 and one or the other of the push bars 19 will engage the breast edge of the lowermost heel-blank in the magazine and move it over the spring 50 or table 23 toward the centering device 45. The lower end of this device normally rests by gravity upon the table 23 and the device as a whole is of sufficient weight to offer such resistance to the movement of the heel-blank (indicated by 52 in the drawing) that the rounded end of the latter, engaging the inclined sides 48^a, will cause the heel-blank to be moved to one side or the other to center the same. As the heel-blank continues to be moved forward, the centering device 45 will be raised, as shown by Figure 2, and its lower ends will ride upon the heel-blank as the latter moves under it. In the continued movement of the heel-blank, its rounded end next engages the projection 41 on dog 40 thereby turning the toe portion of said dog downward, and engagement of the under side of the dog with the heel-blank forces the forward end downward against the resistance of spring 50, this continuing until the flat portion 42 of the dog rests upon the upper surface of the heel-blank. At the time the heel-blank is pressed downward by the movement of dog 40 about its pivot, the under side of its forward portion will be in position over the upper or cutting edge of gouger 20 and as the dog continues to turn to the position shown in Figure 3, the gouger will have been thereby caused to penetrate the heel-blank to the maximum depth that the adjustment provides. In the continued movement of the heel-blank, a section of the under side of the heel-blank will be cut out, in the manner illustrated in Figure 3, the cut extending from the point of incision to the breast of the heel-blank. During the gouging operation, the weight 36 holds the dog 40 in contact with the heel-blank 52 with sufficient force to hold the heel-blank in firm engagement with the gouger. When the heel-blank is passed from under the dog 40, the latter is returned to the normal position shown in Figure 2, by spring 44. The second push bar will then engage another heel-blank in the magazine and the foregoing operations will be repeated.

In order to render the machine capable of accommodating heel-blanks of varying heights, I provide for adjusting the height of the dog 40 relative to the bed plate or table 23. To this end I mount in the arm

35, an adjusting screw 53, the lower end of which bears against the top of the cross-bar 26. By turning this screw in one direction or the other, the arm 35 may be raised or lowered to correspondingly raise or lower the dog 40. Preferably a guard in the form of a bale 54 is mounted on the cross-bar 26 to embrace the arm 35 to prevent the bar from being accidentally moved too far laterally in one direction or the other.

From the foregoing, it will be seen that I provide for automatically causing an incision of uniform depth to be made in successive heel-blanks and the removal of the material from the under side of the heel-blank of a thickness corresponding to the depth of the incision. It will be understood, of course, that the gouger 20 is transversely curved and the cutting edge slightly rounded so that the recess formed in the heel-blank will be of rounded contour to correspond with the shape of the heel portion of the sole which it is to receive. It will further be seen that by causing the heel-blank to be automatically centered, I provide for the correct positioning of the gouge in successive heel-blanks. These blanks, after having been subjected to the gouging operation and placed in a compress, will be subjected to uniform pressure at all points and as indicated above, the objectionable heating or burning of the heel-blank will be prevented.

I claim:

1. In a machine of the class described, in combination with means for moving a heel-blank in a right line, a gouger having its cutting edge located in the plane of movement of said heel-blank, and means for producing relative movement between the gouger and heel-blank when the heel-blank has reached a defined position with respect to the gouger to cause the penetration of the heel-blank by the gouger, whereby, in the continued movement of the heel-blank, material of uniform depth will be removed therefrom.

2. In a machine of the class described, in combination with means for moving a heel-blank in a right line, a gouger having its cutting edge located in the plane of movement of said heel-blank, and means for producing relative movement of a predetermined extent between the gouger and heel-blank when the heel-blank has reached a defined position with respect to the gouger to cause the penetration of the heel-blank by the gouger, whereby, in the continued movement of the heel-blank, material of uniform depth will be removed therefrom.

3. In a machine of the class described, in combination with means for moving a heel-blank in a given path over a gouger having its cutting edge located in the plane of movement of said heel-blank, means for elevat-

ing the forward portion of the heel-blank as it passes over the gouger and means for depressing the heel-blank when it has reached a defined position over the gouger to 6 cause the penetration of the heel-blank by the gouger, whereby, in the continued movement of the heel-blank, material of uniform depth will be removed therefrom.

4. In a machine of the class described, in 10 combination with means for moving a heel-blank in a given path, a gouger having its cutting edge located in the plane of movement of said heel-blank, and means for depressing the heel-blank when it has reached 15 a defined position with respect to the gouger to cause the penetration of the heel-blank by the gouger, whereby, in the continued movement of the heel-blank, material of uniform depth will be removed therefrom.

5. In a machine of the class described, in combination with a support, means for moving a heel-blank thereover, a depressible spring in the line of movement of said heel-blank and projecting beyond the surface of said support, a gouger having its cutting edge located in the plane of movement of said heel-blank and also projecting beyond the surface of said support, and means for 25 depressing the heel-blank against the resistance of said spring when the heel-blank has reached a defined position with respect to the gouger to cause the penetration of the heel-blank by the gouger, whereby, in the continued movement of the heel-blank, material of uniform depth will be removed therefrom.

6. In a machine of the class described, in combination with a horizontal support, a 40 leaf spring secured in said support and having a free end projecting above the surface of the latter, a gouger mounted in said support and having its cutting edge projecting above the surface of the latter beyond the 45 free end of said leaf spring, means for moving the heel-blank over said support and spring, whereby the free end of the latter will elevate the heel-blank at one end to cause it to pass over the gouger, and means for depressing the elevated end of the heel-blank when it has reached a defined position 50 over the gouger to cause the penetration of the heel-blank by the gouger, whereby, in the continued movement of the heel-blank, material of uniform depth will be removed therefrom.

7. In a machine of the class described, in combination with means for moving a heel-blank in a given path, a gouger having its 60 cutting edge located in the plane of movement of said heel-blank, means for automatically centering the heel-blank with reference to the gouger, and means for producing relative movement of a predetermined extent between the gouger and the 65

heel-blank when the heel-blank has reached a defined position with respect to the gouger to cause the penetration of the heel-blank by the gouger, whereby, in the continued movement of the heel-blank, material of uniform depth will be removed therefrom.

8. In a machine of the class described, in combination with means for moving a heel-blank in a given horizontal path, a gouger having its cutting edge located in the plane of movement of said heel-blank, means for elevating the forward end of said heel-blank to cause it to pass over the gouger, a pressure device adapted to be engaged by the forward end of the heel-blank in its movement and to be turned thereby into engagement with the top of the heel-blank to depress it when the heel-blank has reached a defined position over the gouger to cause the penetration of the heel-blank by the gouger, whereby, in the continued movement of the heel-blank, material of uniform depth will be removed therefrom.

9. In a machine of the class described, in combination with means for moving a heel-blank in a given horizontal path, a gouger having its cutting edge located in the plane of movement of said heel-blank, a pivoted pressure device suspended above the path of movement of the heel-blank and adapted to be engaged by the forward end thereof and thereby turned into engagement with the top of the heel-blank to depress it when the heel-blank has reached a defined position over the gouger to cause the penetration of the heel-blank by the gouger, whereby, in the continued movement of the heel-blank, material of uniform depth will be removed therefrom.

10. In a machine of the class described, in combination with means for moving a heel-blank in a given horizontal path, a gouger having its cutting edge located in the plane of movement of said heel-blank, an adjustable member, a pressure device pivotally suspended from said member above the path of movement of the heel-blank and adapted to be engaged by the forward end of the latter, and turned into engagement with the top of the heel-blank to depress the same when the heel-blank has reached a defined position over the gouger to cause the penetration of the heel-blank by the gouger, whereby, in the continued movement of the heel-blank, material of uniform depth will be removed therefrom, and means for adjusting said member to vary the distance of said pressure device from said gouger.

11. In a machine of the class described, in combination with a horizontal support having a yielding member thereon, means for moving a heel-blank over said yielding member and support, a gouger mounted in said support and having its cutting edge located beyond one end of said yielding

- member, a pressure device located in the path of movement of the heel-blank and adapted to be engaged by the forward end thereof and thereby turned into engagement 5 with the top of the heel-blank to depress the same against the resistance of said yielding member when the heel-blank has reached a defined position over the gouger to cause the penetration of the heel-blank by the gouger, 10 whereby, in the continued movement of the heel-blank, material of uniform depth will be removed therefrom.
12. In a machine of the class described, in combination with a horizontal support 15 having a yielding member, means for moving a heel-blank over said yielding member and support, a gravity actuated centering device located in the path of movement of the heel-blank and adapted to be raised by 20 the latter in its forward movement, a gouger mounted in said support and having its cutting edge located in juxtaposition to said yielding device, and a pressure device located in the path of movement of the heel- blank and adapted to be engaged by the forward end thereof and thereby turned into engagement with the top of the heel-blank to depress the same when the heel-blank has reached a defined position over 25 the gouger to cause the penetration of the heel-blank by the gouger, whereby, in the continued movement of the heel-blank, material of uniform depth will be removed therefrom.
- 30 13. In a machine of the class described, in combination with a support having a yielding member mounted therein, means for passing a heel-blank thereover, a gouger having a cutting edge located in juxtaposition to said yielding member, and means for depressing said heel-blank to a predetermined extent when the heel-blank has reached a defined position with respect to the gouger to cause the penetration of the heel-blank by 35 the gouger, whereby, in the continued movement of the heel-blank, material of uniform depth will be removed therefrom.
14. In a machine of the class described, in combination with a horizontal support, a yielding member mounted therein and having one end projecting above the surface thereof, a gouger having a cutting edge projecting above the surface of said support in proximity to the free end of said yielding member, means for moving a heel-blank over said member and support, whereby its forward end will be elevated by said member to pass over said gouger, a centering device located in the path of movement of the heel-blank, and a pivoted dog adapted to be engaged by the forward end of the heel-blank and thereby turned into engagement with the top of the heel-blank to depress the same when the heel-blank has reached a defined position over the gouger to cause 40 45 50 55 60 65 70 75 80 85 90 95 100 105 110 115 120 125 130 the penetration of the heel-blank by the gouger, whereby, in the continued movement of the heel-blank, material of uniform depth will be removed therefrom.
15. In a machine of the class described, in combination with a horizontal support, a yielding member mounted in the support, a gouger having a cutting edge occupying a plane above the yielding member when the latter is depressed, an arm pivotally mounted at one end above said support, a spring-pressed dog pivotally mounted on said arm and adapted to be engaged by the forward end of the heel-blank and thereby turned against the resistance of the spring into engagement with the top of the heel-blank to depress the same when the heel-blank has reached a defined position over the gouger to cause the penetration of the heel-blank by the gouger, whereby, in the continued movement of the heel-blank material of uniform depth will be removed therefrom, and means for adjusting the height of the free end of said arm.
16. In a machine of the class described, in combination with a horizontal support, a magazine mounted above the same and adapted to position a pile of heel-blanks with the lower heel-blank resting on said support, a yielding member mounted in said support, a gouger also mounted in said support and having a cutting edge occupying a plane above said yielding member when the latter is depressed, means movable under said magazine for moving in succession the bottom heel-blank of the pile over said yielding member and support, an automatic centering device located in the path of movement of the heel-blank, and a pressure device also located in the path of movement of the heel-blank and adapted to be engaged by the forward end thereof and thereby turned into engagement with the top of the heel-blank to depress the same against the resistance of said member when the heel-blank has reached a defined position over the gouger to cause the penetration of the heel-blank by the gouger, whereby, in the continued movement of the heel-blank, material of uniform depth will be removed therefrom.
17. In a machine of the class described, in combination with a horizontal support, a yielding member therein, a gouger also mounted in said support and having its cutting edge projecting above the plane of the yielding member when the latter is depressed, means for moving a heel-blank over said yielding member and support, a weighted arm pivotally mounted at one end on a fixed part of the machine and having a dog pivotally mounted on its under side in the path of movement of said heel-blank, whereby, in the movement of the heel-blank, its forward edge will engage said dog and

turn the latter into engagement with the top of the heel-blank to depress the same against the resistance of said yielding member when the heel-blank has reached a defined position 5 over the gouger, to cause the penetration of the heel-blank by the gouger, whereby, in the continued movement of the heel-blank material of uniform depth will be removed

therefrom, and adjustable means for supporting the free end of said arm, whereby, 10 the latter may be raised or lowered to vary the distance of said dog from said gouger.

In testimony whereof, I have hereunto set my hand.

DENNIS PARKS.
